UNITED STATES PATENT OFFICE.

WILLIAM R. KINNEAR, OF COLUMBUS, OHIO.

HORSESHOE.

SPECIFICATION forming part of Letters Patent No. 599,712, dated March 1, 1898.

Application filed April 16, 1897. Serial No. 632,480. (No model.)

To all whom it may concern:

Be it known that I, WILLIAM R. KINNEAR, a citizen of the United States, residing at Columbus, in the county of Franklin and State of Ohio, have invented certain new and useful Improvements in Horseshoes; and I do hereby declare the following to be a full, clear, and exact description of the invention, such as will enable others skilled in the art to which it appertains to make and use the same.

The object of my invention is to provide a shoe of simple and economical form adapted to receive calks that may, when worn, be easily and quickly replaced by new ones, thereby obviating the now common expense of frequently shoeing the horse.

My invention consists, first, of the improved construction of the shoe, and, secondly, in the improved form of calk hereinafter described and claimed.

I have illustrated my improvements in the annexed drawings, in which—

Figure 1 is a plan view of the under side of the shoe with one of the heel-calks removed. Fig. 2 is a sectional view taken on the lines xx of Fig. 1. Fig. 3 is a vertical central sectional view of a modified form of calk. Fig. 4 is a side view of another modification, and Fig. 5 is a side elevation of an instrument that may be employed to remove and insert the calks.

In the several views like characters of reference designate corresponding parts.

1 designates the shoe proper, the body of which is generally flat and thin and made with screw-threaded bosses or projections 2 for the reception of calks 3. The screw-threaded bosses may be of any number; but two at the toe and one at each of the parts of the heel, as shown, will ordinarily suffice. I make the calk hollow, in the form of a short tube, with the edge of its treading part 3^a rather sharp, so as the better to take into the road or ice upon the road, and with a threaded shank 3^b to enter the threaded boss 2 on the shoe proper. Formed upon the under side of the shoe proper and lying parallel to the sides of the shoe, between the toe and heel bosses, are two ribs or beads 4 and 5, the inner rib 4 being of about the same altitude as the bosses, and the outer rib 5 being of less height, as shown. The nail-holes 6 are made in the shoe between these ribs 4 and 5, as indicated.

If desired, the calk may be made with a shoulder 7, as indicated in Fig. 3, at the base 55 of the threaded part, so that when the calk is turned into the shoe said shoulder may be in firm contact with the end of the boss and so relieve the strain on the thread, but when the thread is made large this will not be necessary. The inner wall of the calk is made with a square or other non-circular opening or socket 3^c, located below the outer edge or tread portion of the calk, to receive a fitting-key by which the calk may be turned into or 65 out of the shoe. In placing the socket 3^c below the tread portion of the calk the socket is protected against wear and disfigurement. Such a key is shown in Fig. 5, where the end 8 is indicated as made so as to fit a square 70 hole or socket. The other end of the instrument may be pointed, as shown at 9, and therefore conveniently used to pick out a stone or dirt that may happen to lodge in the cavity of the calk. The socket 3^c is also made 75 to extend beyond or above the tread-face of the shoe when in position, so that should the calk be worn entirely down or even with the shoe a part of the socket will still remain to be engaged by the wrench.

In Fig. 4 I have illustrated a hollow calk according to my invention, having a portion of its tread removed or omitted, so that in its contact with icy pavements the ice shall be penetrated, but not entirely broken, and 85 therefore a firmer and surer hold of the shoe upon the pavement afforded.

The ribs 4 and 5, between the calks, strengthen the shoe, and by making the inner bead or rib of greater altitude than the outer 90 one the nails are more easily driven into place and their heads protected.

With the shoe herein described the shoe proper is nailed to the hoof to remain an indefinite period, and the calks are renewed as 95 fast as they are worn down. To renew the calks does not require the skill of a professional shoer. It may be done as well and as quickly by the hostler or driver of the horse. Thus a large saving of expense and time to 100 owners is effected.

What I claim, and desire to secure by Letters Patent, is—

1. A horseshoe formed of the body portion 1, hollow internally-threaded bosses or projections 2, rib 4 extending between the bosses,

and hollow externally-threaded calks to fit the bosses, the said calks having an internal socket located below the outer edge or tread portion of the calk to receive a wrench, substantially as shown and described.

2. A horseshoe having bosses or projections threaded to receive a calk, and a hollow externally-threaded calk to removably enter said bosses having a sharp tread and its inner end solid or closed and also having an internal polygonal wrench-socket the walls of

which are below or beyond the outer edge or tread portion of the calk, and extend beyond or above the tread-face of the shoe when in position, whereby said polygonal socket is protected against injury from contact with the pavement, substantially as shown and described.

WILLIAM R. KINNEAR.
